US00D491464S

(12) **United States Design Patent**
Porwit

(10) **Patent No.:** **US D491,464 S**
(45) Date of Patent: **** Jun. 15, 2004**

(54) **PRODUCT PACKAGE**

(75) Inventor: **Mark Porwit**, Arlington Heights, IL
(US)

(73) Assignee: **Fibre-Craft Materials Corporation**,
Niles, IL (US)

(**) Term: **14 Years**

(21) Appl. No.: **29/187,349**

(22) Filed: **Jul. 31, 2003**

(51) LOC (7) Cl. **09-03**

(52) U.S. Cl. **D9/415**

(58) **Field of Search** D9/415, 418, 420,
D9/457; 206/461-471, 806, 495, 223, 213,
278, 282, 438, 292, 525, 527, 457, 822
